UNITED STATES PATENT OFFICE.

WILLIAM R. BETHAM, OF CHICAGO, ILLINOIS.

BOX.

1,090,592.

Specification of Letters Patent. Patented Mar. 17, 1914.

Application filed December 26, 1911. Serial No. 667,812.

To all whom it may concern:

Be it known that I, WILLIAM R. BETHAM, a citizen of the United States, residing at Chicago, in the county of Cook and State of Illinois, have invented certain new and useful Improvements in Boxes, of which the following is a specification.

My invention relates to improvements in boxes, and more particularly to a paste-board box for candy providing in its body a base, and a plurality of independent trays permanently but movably connected with the base for movement with respect thereto to give ready access to any one of the trays without disturbing the contents of the others, and to permit effective display of the contents of all of the trays, and providing a cover to coöperate with all of the trays and the base.

One of the objects of my invention is to improve the construction of display boxes to render the same more practicable, structurally and functionally, from the standpoints of manufacture and use, than structures heretofore provided.

To this end, my invention contemplates an arrangement of parts whereby the trays are firmly and permanently pivoted upon the main or base portion of the box so as to be held in closed positions by the cover and give—when the cover is removed and the trays swung to unfolded position—an attractive appearance to the whole display.

Further objects will become apparent from the following description taken in conjunction with the accompanying drawing, wherein—

Figure 1 is a perspective view of the box with the cover removed and some of the trays swung out to display the underlying base; Fig. 2 is a longitudinal vertical section of the closed box and cover; and Fig. 3 is a detail on line 3—3 of Fig. 2.

In the drawings, 5 indicates the base member of the box body having the usual side, end, and bottom wall portions, and preferably provided with the exterior lip or flange 6 around the bottom for coaction with the cover.

The trays 7—7 may, as shown, be arranged advantageously in two tiers of two trays each, the trays having an aggregate area, in plan, equal to that area bounded by the vertical walls of the underlying base 5. The trays may be made of any desired height, the height of the box being equal to the ag-

gregate height of the body and the two superposed trays. Though this particular division of the space above the base 5 is advantageous in properly balancing the device when it is opened and making for attractive display of the contents, it will be apparent that some features of my invention are not affected by the particular size, shape, and location of the trays above the base of the box. I mount the trays so that each may be swung out to desired position independently of its fellows, the trays of each tier being mounted for pivotal movement with respect to the vertically contiguous tray or trays and to the base, the two pivotal axes lying within the corners of the base preferably at the opposite ends of the same side wall of the base, so that the trays may be spread out upon both sides of the body. Specifically, I span the corners at the rear of the box 5 with small webs 8 of generally triangular shape, each perforated to receive an appropriate pivot post 9 which extends upwardly through the bottom walls of the superposed trays and on which the trays turn. Each pivot post has near its ends washers 10—10 over which the ends of the post are upset, firmly pressing together the parts embraced between the washers. For advantageous mounting of the trays upon the post, I provide upon the trays webs 8', corresponding with the webs 8 of the base, except upon the upper tray which need be engaged only at the bottom. It will be noted that there is provided an advantageous frictional engagement between the webs 8 and 8' and the bottoms of the overlying trays, so that the trays resist displacement from any position to which they have been intentionally moved, and that the attaching means is compact and durable, and is visible only when the upper tray is emptied.

A cover 11 is provided to fit down over the body of the box, comprising the base 5 and the trays 7—7 when the trays are folded in, the side walls of the cover preferably tapering inwardly toward the point of junction between the side walls and ledge 6 of the base 5. It may be observed that the tapering shape of the cover avoids frictional engagement between the cover and the upper trays during removal of the cover, so that the trays, mounted at their extreme corners, may not be twisted upwardly at the opposite ends, yet the cover clearance is not great enough to permit any considerable

displacement of the trays in shipment or handling. At the edge of the cover 11, where it contacts with the trays in the process of removal, any undue sticking of the tray to the cover may be obviated by gripping the tray under the edge of the cover, which is the only possible point of sticking.

While I have described an embodiment of my invention, it will be understood that features of the invention may be variously embodied, and that changes may be made in the non-essential details without departing from the spirit of the invention and within the scope of the appended claims.

15. What I claim is:

1. In a paste-board box of the character described, a base having side and end walls and a top web overlying a corner of said base and constituting a pivot-supporting and tray-bearing means leaving the interior and exterior surfaces of the vertical walls of said base unoccupied, a pivot and bearing on the web connected with said web, and a tray mounted upon said pivot for pivotal movement over the web relative to the base.
2. In a paste-board box of the character described, a base having side and end walls and a horizontal top-web at a corner of said base, a tray superposed on said base bearing on said web and provided with a similar web, another tray similarly arranged above the first tray, and pivotal connections between the bottom of each tray and the subjacent web, fixing said elements in unalterable vertical relation and leaving each tray free for pivotal movement in its own plane, each said web constituting a pivot-receiving and tray-bearing means carried by meeting side and end walls of the box and tray leaving the space upon both sides of said walls unoccupied.

3. In a device of the character described, the combination of a base, a tray pivoted to the base adjacent its corner for lateral move-

ment relative to the base, and a cover having top, side, and end walls, the lower edges of said side and end walls fitting snugly against the base, and the inner surface of said walls being spaced from the adjacent outer surfaces of the base and trays when the trays are folded in above the base.

4. In a box, the combination of a base having side and end walls and top-webs spanning two corners thereof, trays arranged in tiers, each tier comprising a pair, top-webs in the appropriate corners of all trays intermediate the base and the topmost tray, pivot means for connecting the bottom of each tray with the corner web of the subjacent tray, whereby each tray may swing pivotally in its plane and be supported upon a subjacent corner web, said trays when folded conforming to the plan area of the base, and a cover having a bottom opening conforming to the plan area of the base, the walls of said cover diverging from said bottom opening to leave a clearance between the trays and the cover.

5. An article of manufacture comprising a cardboard structure having a bottom, and vertical side and end walls, the cardboard of one of said vertical walls at its upper edge adjacent one corner of the structure having an extension bent inwardly at right angles to the wall and connected to the vertical wall which meets the extension-carrying vertical wall at that corner, to provide a horizontal cardboard web, said web being perforated to provide support for a pivot post, and a pivot post carried by said web for pivotal support of other like structures.

In testimony whereof I hereunto set my hand in the presence of two witnesses.

WILLIAM R. BETHAM.

In the presence of—

MARY F. ALLEN,
W. LINN ALLEN.
